(57) CLAIM

The ornamental design for an edge protector as shown and described.

DESCRIPTION

FIG. 1 is a perspective view of an edge protector showing my new design;

FIG. 2 is another perspective view thereof;

FIG. 3 is a top view thereof;

FIG. 4 is a bottom view thereof;

FIG. 5 is a top view thereof showing an unassembled form; and,

FIG. 6 is a perspective view of the edge protector coupled to a desk.

The broken line portions of the edge protector in FIGS. 1-2 and 4-6 represent unclaimed portions of the claimed design and form no part thereof. The broken lines of the desk in FIG. 6 illustrate unclaimed environment and forms no part of the claimed design.

1 Claim, 5 Drawing Sheets
